UNITED STATES PATENT OFFICE

126,741

DESIGN FOR A PAIR OF GOGGLES OR SIMILAR ARTICLE

Joseph Brunetti, Carlstadt, N. J., assignor to Columbia Protektosite Co., Incorporated, Carl-stadt Township, Bergen County, N. J., a corporation of New Jersey

Application December 29, 1939, Serial No. 89,192

Term of patent 7 years

To all whom it may concern:

Be it known that I, Joseph Brunetti, a citizen of the United States and resident of Carlstadt, in the county of Bergen and State of New Jersey,
have invented a new, original, and ornamental Design for a Pair of Goggles or Similar Article of which the following is a specification, reference being had to the accompanying drawing, forming part thereof, and in which:

Fig. 1 is a front elevational view of the pair
of goggles showing my new design;

Fig. 2 is a top plan view of the goggles shown in Fig. 1; and

Fig. 3 is a side elevational view of the goggles shown in Fig. 1.

What I claim is:

The ornamental design for a pair of goggles
or similar article, substantially as shown.

JOSEPH BRUNETTI.
